UNITED STATES PATENT OFFICE.

GEORGE H. FOLLOWS, OF CINCINNATI, OHIO, ASSIGNOR TO THE MILLER, DU BRUL & PETERS MANUFACTURING COMPANY, OF SAME PLACE.

DESIGN FOR A CIGAR WRAPPING AND CUTTING TABLE SUCTION-VALVE.

SPECIFICATION forming part of Design No. 35,137, dated October 1, 1901.

Application filed June 28, 1901. Serial No. 66,451. Term of patent 14 years.

To all whom it may concern:

Be it known that I, GEORGE H. FOLLOWS, a citizen of the United States, residing at Cincinnati, in the county of Hamilton, State of Ohio, have invented and produced a new and original Design for a Cigar Wrapping and Cutting Table Suction-Valve, of which the following is a specification, reference being had to the accompanying drawings, forming part thereof.

Figure 1 is a front elevation of a suction-valve embodying my new design. Fig. 2 is a vertical central section through the same. Fig. 3 is a top plan view of Fig. 1, and Fig. 4 is a side elevation of the same.

As shown in the drawings, the leading or material features of my design consist of the body 3, having a semi-elliptical appearance in side elevation, with top flanges 8, large and small legs 1 and 2, disposed, with reference to the body 3, to one side of the vertical axis of the body and in such position that a center line A, drawn through the leg 1, and a center

line B, drawn through the leg 2, will form the angles shown with the plane of the face 4 of the body 3. Immediately above the juncture of the center lines A and B and within the body 3 is formed a circular opening 5, from one side of which projects an arm 6 to about the center of said opening, in the outer end of which is formed a perforation 7, directly in line with the center line B of the leg 2.

8 is a flange projecting from each side of the top of the body 3.

Having described my invention, what I claim as new, and desire to secure by Letters Patent, is—

The design for a suction-valve for cigar wrapping and cutting tables as shown and described.

The foregoing specification signed this 24th day of June, 1901.

GEORGE H. FOLLOWS.

In presence of—

N. DU BRUL,
W. M. BEINHART.
